SHOE PRESSING APPARATUS

Filed Oct. 30, 1928

UNITED STATES PATENT OFFICE

MINARD C. HOSKIN, OF AKRON, OHIO, ASSIGNOR TO THE B. F. GOODRICH COMPANY,
OF NEW YORK, N. Y., A CORPORATION OF NEW YORK

SHOE-PRESSING APPARATUS

Application filed October 30, 1928. Serial No. 315,956.

This invention relates to apparatus for pressing shoes, and especially to devices for compacting the rubberized sole-margin of a lasted upper or shoe-lining and adhering it 5 to an insole mounted on the last and underlying said margin. The apparatus also may be advantageously used for pressing filler-soles onto insoles, and in other operations where it is desired to exert pressure upon the 10 bottom of the shoe only. The invention is, in part, an improvement upon the invention of V. H. Bodle, Patent No. 1,657,296.

The chief object of the invention is to provide improved shoe-pressing apparatus by 15 which the sole portion of a shoe may be more evenly and effectively pressed than in apparatus previously used. A more specific object is to apply different pressures to adjacent regions of a shoe sole. A further object 20 is to provide simple apparatus for the purpose mentioned which will be long-lived and not subjected to frequent breakage or other failures.

Of the accompanying drawings:

25 Fig. 1 is a side elevation of apparatus embodying my invention, in its preferred form, in operative relation to the work, and the work therein, parts being sectioned and broken away.

30 Fig. 2 is a sectional detail of a portion of the apparatus.

Fig. 3 is a plan view of the sole-pressing structure and adjacent parts.

Referring to the drawings, 10 is a ram 35 guide in which is mounted a ram 11 carrying on its top a pair of parallel, spaced-apart metal strips 12, 12 which support the sole-pressing structure. Extending upwardly from one side of the guide 10 is a bracket 13 40 of which the upper end portion extends laterally over the ram and has pivoted thereon at 14 an L-shaped hold-down member 15 of which one arm is adapted to bear upon the toe portion of a shoe 16 mounted upon a last 45 17 and of which the other arm is adapted to bear upon the top of the last to hold the last and shoe against the upward pressure of the sole-pressing structure when the latter is raised by the ram.

50 The sole pressing structure comprises a

heel-pressing block 18 of rigid material such as metal, and a toe-pressing block 19 of like material, the heel-pressing block being immovably mounted with relation to the ram and the toe pressing block being so mounted 55 as to be movable with relation to the heel-pressing block.

The heel-pressing block 18 is mounted upon a base-plate 20, and the toe-pressing block 19 is mounted upon an adjacent base-plate 60 21 which is hingedly connected to the base-plate 20 for universal movement with relation thereto at a point somewhat in front of the middle of the shoe. The base-plate 20 is provided with an underlying spacer-plate 22 and the latter and the base plate 20 are secured to a supporting plate 23 mounted upon and secured to the supporting strips 12, the plate 23 also underlying the base-plate 21. 70

The hinged connection between the respective base-plates 20, 21 comprises a stud 24 which is threaded into the margin of the base-plate 20 adjacent the base-plate 21, said stud being formed with a head which is a portion 75 of a sphere that is cut away to provide substantially flat top and bottom faces. The head of the stud 24 extends into a circular recess 25 formed in the base plate 21, and opening onto the margin thereof, the flat 80 faces of the stud-head being parallel with the planes of the respective faces of the plate 21 and lying wholly between said planes. The wall of the recess 25 is arcuate and concentric with the head of the stud 24, and the latter 85 fits loosely therein to allow freedom of movement of the base plate 21.

A spherical segment 26, concentric with the head of the stud 24 is secured to the bottom face of the base plate 21 and extends across 90 the recess 25, said segment resting upon the supporting plate 23 and providing a pivot for angular movement of the plate 21 in any direction.

The free end of the base-plate 21 normally 95 is urged upward by a stiff compression spring 27 which is seated in a suitable cup or well 28 supported by the supporting-plate 23, the upper end of the spring engaging the bottom face of the plate 21, around a centering stud 100.

29 which projects therefrom. The upward movement of the plate 21 is limited by a threaded stud 30 projecting downwardly from said plate and extending through a narrow slot 31 in the supporting plate 23, the lower end of the stud 30 beneath the plate 23 being provided with an adjustable nut 32.

30 Positioned between the heel-pressing block 18 and toe-pressing block 19 is a cushion 33 of yielding, elastic material such as rubber, said cushion being adhered or vulcanized to said pressing blocks 18, 19 and to their underlying base-plates 20, 21. The marginal and surface contours of the cushion 33 conform generally to the corresponding portions of a large size shoe, the apparatus being adapted to operate upon shoes of all adult sizes.

31 As shown in Fig. 2 with relation to the heel-pressing block, the top surface of the cushion 33 normally extends somewhat above the top surface of the heel-pressing block and toe-pressing block at the respective lines of junction therewith.

32 In the operation of the apparatus, the ram 11 being lowered, the work is placed upon the pressing structure, which, because of the expansion of the spring 27, has its toe-pressing block 19 in an elevated position and its intermediate, cushion portion 33 curved on a smaller radius than the normal curvature of the bottom of a shoe, with the result that the latter rests with its toe and heel portions upon the respective toe and heel-pressing blocks and its intermediate portions standing clear 35 of the cushion 33.

33 The ram 11 is then raised to carry the shoe into engagement with the stationary hold-down member 15 and thereafter to forcibly press the shoe between the latter and the sole-pressing structure. As pressure is brought to bear upon the heel and toe portions of the shoe, where the shoe-upper's margin is most gathered, the toe-pressing block moves downward against the yielding pressure of the 40 spring 27 and swivels laterally or angularly upon the pivot 26 to accommodate itself to the contour of the shoe bottom so as accurately to fit the latter. Before the toe-pressing member 19 reaches the limit of its downward movement wherein the toe and heel-pressing members fully engage the shoe, the shank of the shoe engages the cushion 33 and slightly compresses the same, so that when the apparatus attains the final position shown 45 in Fig. 1 of the drawings, the entire shoe bottom is under pressure.

34 The pressure preferably is greatest at the heel of the shoe where the full pressure of the ram 11 is transmitted to the shoe through the 50 unyielding heel-pressing block 18. The pressure at the toe of the shoe is transmitted through the yielding but stiff spring 27 and is almost as great as at the heel. The pressure on the shank of the shoe is transmitted 55 through the cushion 33 and is lighter than the

60 pressure at the toe and heel portions, but is sufficient to compact the shoe parts in this region where the shoe upper lies smoothly upon the insole. The elasticity of the cushion 33 permits it to conform to the contour of the work and yet to apply adequate pressure to the entire area thereof.

65 When the pressure has been maintained for a sufficient time to effect the desired result upon the work the ram is lowered, the work removed, and the operation as described may be repeated.

70 My invention is susceptible of modification within the scope of the appended claims.

75 I claim:

80 1. Shoe-pressing apparatus comprising a pair of members of which one member is movable with relation to the other member to compress a shoe mounted therebetween, and a sole-pressing structure carried by one of said members and comprising an unyielding pressing member fixedly mounted thereon and a pressing member mounted for movement with relation to said fixedly mounted member, said pressing members engaging respective portions of the shoe sole, for applying different pressures to adjacent portions thereof.

85 2. Shoe-pressing apparatus as defined in claim 1 in which the relatively movable member of the sole-pressing structure is yieldingly mounted upon its support.

90 3. Shoe-pressing apparatus comprising a pair of members of which one member is movable with relation to the other member to compress a shoe mounted therebetween, and a sole pressing structure mounted on one of said members and comprising an unyielding pressing member of rigid material and a pressing member of yielding material, said pressing members engaging respective portions of the shoe sole, for applying different pressures to different portions thereof.

95 4. Shoe-pressing apparatus comprising a stationary member and a movable member adapted to support and press a shoe mounted therebetween, and a sole pressing structure mounted on one of said members and comprising a heel-pressing member fixedly mounted upon its support, a toe-pressing member yieldingly mounted for movement with relation to the heel-pressing member, and a yielding shank-pressing member intermediate said toe and heel-pressing members.

100 5. Shoe-pressing apparatus as defined in claim 4 in which the shank-pressing member comprises yielding material.

105 6. Sole-pressing apparatus comprising a heel-pressing member, a toe-pressing member, a shank-pressing member intermediate said members, and means for pressing the work against said members, said shank-pressing member comprising yielding material so mounted and arranged as to be put under pressure by the shoe before the toe and heel

portions thereof fully engage their respective pressing members.

7. Shoe-pressing apparatus comprising a stationary member and a movable member adapted to compress a shoe mounted therebetween, and a sole pressing structure mounted on one of said members and comprising a heel-engaging member fixedly mounted on said member, a pivotally mounted toe-engaging member, an intermediate flexible and yielding shank-engaging member secured to the aforesaid toe and heel engaging members, and yielding means mounted behind the pivoted toe-engaging member for urging it and the adjacent portion of the shank-engaging member toward the work.

In witness whereof I have hereunto set my hand this 27th day of October, 1928.

MINARD C. HOSKIN.
